FIRE EXTINGUISHING APPARATUS

Eric Geertz, Aurora, Ill., assignor to Cardox Corporation, Chicago, Ill., a corporation of Illinois

Original application May 20, 1938, Serial No. 209,151. Divided and this application November 17, 1938, Serial No. 241,035

13 Claims. (Cl. 169—11)

This invention relates to new and useful improvements in apparatus for employing and making available for use liquid carbon dioxide as a fire extinguishing medium, and is a division of my application Serial No. 209,151, filed May 5, 1938.

Carbon dioxide is commonly used at the present time as a fire extinguishing medium. When it is essential to have available for use large quantities of carbon dioxide, the prevailing practice is to store the liquid carbon dioxide in comparatively small cylinders or drums which are arranged and interconnected to form a bank or battery. The carbon dioxide is discharged from the top of the several cylinders in the form of gas. The temperature of the carbon dioxide is permitted to vary in accordance with variations in the temperature of the surrounding atmosphere and, for that reason, the cylinders must be constructed to withstand high working pressures. Due to this lack of control of the temperature and pressure of the stored carbon dioxide, it has not been allowable to fill the internal volume of the cylinders with more than 68% of liquid. The container weight and cost per pound of capacity, therefore, is very high.

The effectiveness of carbon dioxide as a fire extinguishing medium, of course, depends on its ability to smother the fire by excluding oxygen. Carbon dioxide gas, although heavier than air, is seriously affected by the currents of heated air which rise from the fire and for that reason, the hotter the fire, the less effective or efficient carbon dioxide gas is as an extinguishing medium. The discharge of carbon dioxide gas from the battery of cylinders will bring about evaporation of additional liquid in the cylinders. This vaporization of liquid carbon dioxide in the cylinders will result in refrigerating the remaining liquid. If the discharge of gas continues for a sufficient length of time, the temperature of the remaining carbon dioxide liquid will be lowered to -70° F., the temperature at which the liquid carbon dioxide will solidify, and further discharge of the extinguishing medium will cease. This solidification of the remaining liquid carbon dioxide will occur as a result of continuous or substantially continuous discharge of approximately three quarters of the original quantity of liquid.

Therefore, in addition to being unable to fill the entire internal volume of the cylinders with liquid carbon dioxide, approximately one-quarter of the liquid which is stored in the cylinders is not available for use if the fire being extin-

guished is of a character to require discharge of more than three-quarters of the original quantity.

The primary object of this invention is to provide apparatus for making carbon dioxide available for use as a fire extinguishing medium without encountering the defects and disadvantages inherent in present day methods.

A further important object of the invention is to provide apparatus for employing and making available for use at a low storage cost, large quantities of liquid carbon dioxide at controlled constant subatmospheric temperatures and corresponding low vapor pressures.

A still further object of the invention is to provide apparatus for employing liquid carbon dioxide as a fire extinguishing medium in which the liquid is conditioned so as to produce a much higher percentage of yield of snow when discharged to the atmosphere than is possible with methods and apparatus now in common use.

Another object of the invention is to provide apparatus for employing carbon dioxide as a fire extinguishing medium wherein a larger quantity by weight of carbon dioxide per unit of container volume and weight is provided than has been possible heretofore.

Still another object of the invention is to provide a fire extinguishing medium which is especially effective in combating gasoline, oil, wood, electrical and coal mine fires; which is especially effective in preventing the occurrence of re-flash in any type of fire, and which will enable fire fighters to more closely approach extremely hot fires.

Other objects and advantages of the invention will be apparent during the course of the following description.

In the accompanying drawing forming a part of this specification and in which like numerals are employed to designate like parts throughout the same,

The figure diagrammatically illustrates the fire extinguishing apparatus embodying this invention and its method of use to extinguish different types or kinds of hostile fires.

In the drawing, wherein for the purpose of illustration are shown the preferred embodiments of this invention, the reference character 5 designates a building which is intended to be representative of all types and styles of building in which fire hazards may exist; for example, private residences, apartment houses, office buildings, garages, service and repair shops, manufacturing plants, etc. Within this building

5, there is illustrated a room or confined space 6 which the owner or occupant desires to protect from a hostile fire by means of a sprinkling system 7, with its discharge nozzles 8, or by 5 means of an ambulant discharge which may take the form of a flexible hose 9 with a suitable discharge nozzle 10. Within the building 5, there also is illustrated an object 11 which may take the form of any stationary or substantially stationary piece of equipment or apparatus which can be protected by a non-ambulant discharge device 12 which may assume any desired and efficient form for accomplishing the intended results.

15 Exteriorly of the building 5, there is illustrated a storage pile 13 which may be formed of any combustible material, such as coal, wood, grain, or the like. This storage pile 13 may be protected from fire hazards by means of a non-ambulant system of discharge nozzles 14 associated with a supply line 15 or by means of an ambulant discharge device which may take the form of the long perforated pipe 16 which is connected to a flexible supply conduit 17.

25 While the objects designated by the reference characters 5, 6, 11 and 13 are representative of all different types of objects or things which should be protected from fire hazards, it is to be understood that the use of this fire extinguishing system and method is not in any way to be limited to the protection of objects and things of the character which has been illustrated, but is applicable to all objects and things which require fire protection. It is to be understood, also, that 30 this system and method is not to be limited to the particular forms of discharge devices which have been diagrammatically illustrated.

Properly located with respect to the various sources of hostile fires is a heavily insulated container 18 of large capacity. This container unit 40 may consist of one tank or a series of tanks enclosed in a single heat insulating shell. The container unit 18 preferably should have a capacity of several hundred pounds of liquid carbon dioxide, and may contain several tons of the liquid, depending upon the character of the hazard to be protected. Of course, where the system is employed to protect large apartment houses, office buildings, or a factory, it may be necessary to 45 provide two or more of the container units 18. It is to be considered that such an expansion of the illustrated system falls within the scope of the invention. This container unit 18 should be designed to withstand a working pressure of 50 approximately 500 pounds per square inch, or, more specifically, the vapor pressure at 32° F., which is 505 pounds per square inch absolute. Of course, container units capable of withstanding a higher working pressure may be employed, 55 but as the ability to withstand greater internal pressures is not essential or desirable, the use of container units adapted to withstand working pressures appreciably in excess of 500 pounds per square inch will materially add to the initial cost of the installation and will thereby eliminate 60 from or deprive the system of one of its most valuable features.

Properly communicating with the lower portion of the container unit 18 is a pipe line 19 70 which extends to a readily accessible location and is provided at its extremity with a coupling 20 by means of which a transportable container, such as a railway tank car or road tank vehicle, may be connected to the said unit. The railway 75 tank car or road vehicle is intended to transport

from a suitable source of supply to the location of the coupling 20, liquid carbon dioxide maintained at a desired subatmospheric temperature, not to exceed 32° F., at the corresponding vapor pressure. This low temperature liquid carbon dioxide is charged by any suitable method or means into the storage container unit 18. By transporting the liquid carbon dioxide at this low temperature and vapor pressure, a great reduction in the weight of the transport container 10 per ton of capacity may be provided, with the result that handling costs are considerably lower than can be obtained when the carbon dioxide is transported at the fluctuating temperatures and corresponding vapor pressures which would result if the temperature of the liquid carbon dioxide being transported were permitted to vary 15 with the temperature variations of the surrounding atmosphere.

One of the features of this invention is to maintain the liquid carbon dioxide stored in the container unit 18 at a subatmospheric temperature which will not exceed 32° F., and preferably to maintain the stored liquid at the temperature at which it is charged into the unit 18. In view of 20 this fact, it is possible to substantially fill the internal volume of the unit 18 with liquid carbon dioxide notwithstanding the low working pressure of the unit. This makes possible the storage of a much larger quantity by weight of 25 carbon dioxide per unit of container volume than would be possible if the carbon dioxide were stored at atmospheric temperature. It also makes possible a much lower cost per unit of 30 storage capacity.

Associated with the container unit 18 are two different means for maintaining the liquid carbon dioxide at its charging temperature. One of these means consists of a standard commercial refrigerating plant 21 which has its evaporator coil 22 arranged within a dome 23 which is in open communication with the top of the container unit 18. As it is impossible to insulate the container unit against the penetration of any heat whatsoever, the heat which does penetrate 45 will cause some of the liquid carbon dioxide to evaporate. The gas which forms as a result of this vaporization will rise from the liquid bath and will contact the coil 22. This contacting of the gas with the surface of the coil will cause 50 the gas to condense and the condensation will be returned by gravity to the liquid bath. It has been determined that a coil of much less surface area can be employed with this arrangement than would be possible if the coil 22 were located beneath the surface of the liquid bath. By such 55 refrigeration storage of any quantity of carbon dioxide may be had over indefinite periods with no gas loss whatsoever.

The second means for maintaining the liquid carbon dioxide at the sub-atmospheric temperature at which it is charged in the container unit 18 consists of the pop-off or relief valve 24. This valve 24 may be of any desired and well known construction and is intended to be set or adjusted to open at the predetermined vapor pressure which corresponds with the temperature at which it is desired to maintain the liquid carbon dioxide.

As heat penetrates the insulation surrounding 70 the container unit 18, some of the liquid is vaporized and the vapor pressure will rise to the point at which the valve 24 will operate. When the valve opens, carbon dioxide gas will be discharged therethrough to the atmosphere. This 75

bleeding of gas to the atmosphere will be accompanied by vaporization of a like amount of the remaining liquid carbon dioxide. This vaporization is accompanied by or results from absorption 5 of heat from the remaining liquid and brings about refrigeration of this liquid. This refrigeration of the liquid lowers its temperature and the corresponding vapor pressure until the pressure drops below the operating pressure of the 10 valve 24.

It will be appreciated, therefore, that at the expense of the loss of a comparatively small fraction of the stored liquid, the remaining liquid may be maintained at the desired storage temperature. 15 This loss of carbon dioxide is not excessive and can be readily calculated since it would be the ratio of the heat loss in B. t. u. per hour to the latent heat of carbon dioxide at the stored temperature. For example, at 0° F., the latent 20 heat is 120 B. t. u. per pound. A typical storage unit of approximately eight tons liquid carbon dioxide capacity has a rate of heat penetration through the insulation of approximately 1,200 B. t. u. per hour. Thus, the gas loss involved 25 in maintaining the low pressure in the container unit would be a ratio of 1,200:120, or approximately ten pounds per hour. The loss in this typical case amounts to approximately 1½% in each twenty-four hours. This loss is less than 30 the sublimation loss usually encountered in storing and handling solid carbon dioxide in the form of "dry ice".

It will be appreciated that the refrigerating unit 21 and its cooling coil 22 may be employed 35 in combination with the pop-off or relief valve 24 to provide several different modes of operation. For example, it is very desirable to employ a pop-off valve 24 as a safety device which will function in the event of failure of the refrigerating apparatus. It will be appreciated, of course, that the refrigerating apparatus will be provided with any conventional form of temperature or pressure control which will cause the refrigerating apparatus to operate periodically 40 only when it is necessary to extract heat from the carbon dioxide stored in the unit 18. This automatic control, not shown, for the refrigerating unit can be set to maintain the carbon dioxide at a desired subatmospheric temperature. 45 The relief valve 24, operating in combination with the refrigerating apparatus, can be set to open at a pressure in excess of the pressure at which the refrigerating apparatus will start to operate. Therefore, in the event of failure of 50 the refrigerating apparatus, the valve 24 will operate to effect cooling of the carbon dioxide as a result of bleeding of gas to the atmosphere.

Of course, other methods of employing a relief valve in combination with a refrigerating unit 60 may be used. For example, the cooling coil 22 may be connected in a refrigerating system which is employed for other purposes in connection with the building in which it is housed. This refrigerating system may be operated with minimum and maximum load periods. It may be desirable, therefore, to operate the coil 22 for maintaining the carbon dioxide refrigerated only during the minimum load period of the refrigerating apparatus. The relief valve then would be 65 a more important adjunct to the successful operation of the fire extinguishing apparatus. In any mode of operation where a relief valve is employed at least in part to maintain the carbon dioxide refrigerated, the container unit 18 should 70 be serviced periodically by a distributor of the

low temperature carbon dioxide for the purpose of maintaining the container unit 18 properly filled with the fire extinguishing medium.

Suitable manually controlled valves 25 are located at strategic points in the main supply or pipe lines 26 while a conventional expansion valve 25' is employed in the lines 27 of the refrigerating apparatus. By means of valves 25, selective delivery of the refrigerating medium to the various pipes of discharge devices may be 10 provided as desired.

It has been determined by extensive experimental work that liquid carbon dioxide discharged at a temperature which does not exceed 32° F., is a much more efficient and effective fire extinguishing medium than carbon dioxide gas released at atmospheric temperature. For example, a much higher percentage of yield of snow is obtained with the liquid carbon dioxide released at a subatmospheric temperature. Theoretically, 20 carbon dioxide gas released at 70° F. produces 29% snow, while liquid carbon dioxide released to the atmosphere at 0° F. produces 60% snow. Of course, the lower the temperature at which the liquid carbon dioxide is discharged, the greater 25 the percentage of yield of snow. This increased yield of snow provides a heavier blanket for smothering the fire by excluding oxygen from the same, and is not displaced by the natural air currents rising from the fire. This great yield 30 of snow provides the discharge medium with greater mass which permits the medium to be directed at a fire with a greater velocity to more effectively penetrate the rising air currents and to permit the medium to be projected greater 35 distances.

The snow sublimes at a relatively slow rate and thus prolongs the time it will be effective to exclude oxygen from the material which has been burning. This feature plus the availability of 40 the lower temperature of the liquid carbon dioxide to cool the parts which have been heated by the fire, are very effective in preventing reflash. The increased cooling effect the larger yield of snow has upon the material being consumed by the fire, permits fire fighters to more closely approach the location of the fire. The density of carbon dioxide stored at low temperatures as compared to its density when released to the atmosphere gives a much greater increase 45 in volume than is provided when the carbon dioxide is stored at atmospheric temperature. The density of liquid carbon dioxide at 0° F. is 64 pounds per cubic foot, and when expanded in the atmosphere, its density is 0.12 pound per 50 cubic foot. Carbon dioxide stored at this low temperature, therefore, increases in volume 540 times. The expansion of carbon dioxide stored at 70° F. is only about one-half as great as the expansion which occurs when the carbon dioxide 55 is stored at 0° F.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described my invention, I claim:

1. A fire extinguishing system comprising an 70 insulated storage container having a working pressure substantially below the vapor pressure of carbon dioxide at atmospheric temperature and adapted to be filled substantially to its volumetric capacity with liquid carbon dioxide at a 75

subatmospheric temperature, the corresponding vapor pressure of which will not exceed the working pressure of the container, means for effecting refrigeration of the carbon dioxide while maintaining all of the same stored in said container by condensing vapors in the vapor space of said container at a rate which will prevent a rise in vapor pressure above the working pressure of the container, and means for conducting the liquid carbon dioxide at approximately its stored subatmospheric temperature to a point of use.

2. A fire extinguishing system comprising an insulated storage container of large volumetric capacity having a working pressure not to exceed approximately 500 pounds per square inch absolute and adapted to be filled substantially to its volumetric capacity with liquid carbon dioxide at a subatmospheric temperature not to exceed 32° F., means for effecting refrigeration of the carbon dioxide while maintaining all of the same stored in said container by condensing vapors in the vapor space of said container at a rate which will prevent a rise in vapor pressure above the working pressure of the container, and means for conducting the liquid carbon dioxide at approximately its stored subatmospheric temperature to a point of use.

3. A fire extinguishing system comprising an insulated storage container adapted to be filled substantially to its volumetric capacity with liquid carbon dioxide at a subatmospheric temperature, mechanical means for effecting refrigeration of the carbon dioxide stored in said container, while maintaining all of the same confined against loss, by reconverting to liquid the vapors which are formed as a result of absorption of heat through the insulation of the container, and means for conducting the liquid carbon dioxide at substantially its stored subatmospheric temperature to a point of use.

4. A fire extinguishing system comprising an insulated storage container adapted to be filled substantially to its volumetric capacity with liquid carbon dioxide at a subatmospheric temperature not to exceed 32° F., mechanical means for effecting refrigeration of the carbon dioxide stored in said container, while maintaining all of the same confined against loss, by reconverting to liquid the vapors which are formed as a result of absorption of heat through the insulation of the container, and means for conducting the liquid carbon dioxide at its stored subatmospheric temperature to a point of use.

5. A fire extinguishing system comprising an insulated storage container having a working pressure substantially below the vapor pressure of carbon dioxide at atmospheric temperature and adapted to be filled substantially to its volumetric capacity with liquid carbon dioxide at a subatmospheric temperature, the corresponding vapor pressure of which will not exceed the working pressure of the container, a mechanical refrigerating apparatus including an evaporator coil arranged in the vapor space of the insulated storage container to prevent a rise in vapor pressure above the working pressure of the container by condensing vapors coming in contact with said coil and returning the condensation by gravity directly to the liquid bath in the container, and means for conducting the liquid carbon dioxide at substantially its stored subatmospheric temperature to a point of discharge.

6. A fire extinguishing system comprising a storage container including a vapor receiving dome and having a working pressure substantial-

ly below the vapor pressure of carbon dioxide at atmospheric temperature adapted to be filled substantially to its volumetric capacity with liquid carbon dioxide at a subatmospheric temperature, the corresponding vapor pressure of which will not exceed the working pressure of the container, insulating means for the entire container, a mechanical refrigerating apparatus including a cooling coil arranged in the vapor receiving dome of the container and operating to prevent a rise in vapor pressure above the working pressure of the container by condensing vapors coming in contact with said coil and returning the condensation by gravity directly to the liquid bath, and means for conducting the liquid carbon dioxide at a subatmospheric temperature to a point of discharge.

7. A fire extinguishing system comprising an insulated storage container having a working pressure substantially below the vapor pressure of carbon dioxide at atmospheric temperature and adapted to be filled substantially to its volumetric capacity with liquid carbon dioxide at a subatmospheric temperature, the corresponding vapor pressure of which will not exceed the working pressure of the container, a mechanical refrigerating apparatus including a cooling coil arranged in the vapor space of the insulated storage container to prevent a rise in vapor pressure above the working pressure of the container by condensing vapors coming in contact with said coil and returning the condensation by gravity directly to the liquid bath, a relief valve in communication with the vapor space of the container and set to bleed vapor from the container when the vapor pressure in the container rises above the pressure which corresponds with the temperature at which the refrigerating apparatus is intended to maintain the stored carbon dioxide but before the vapor pressure reaches the working pressure of the container, and means for conducting the liquid carbon dioxide at substantially its stored subatmospheric temperature to a point of discharge.

8. A fire extinguishing system comprising a storage container including a vapor receiving dome and having a working pressure substantially below the vapor pressure of carbon dioxide at atmospheric temperature adapted to be filled substantially to its volumetric capacity with liquid carbon dioxide at a subatmospheric temperature, the corresponding vapor pressure of which will not exceed the working pressure of the container, insulating means for the entire container, a mechanical refrigerating apparatus including a cooling coil arranged in the vapor receiving dome of the storage container to prevent a rise in vapor pressure above the working pressure of the container by densing vapors coming in contact with said coil and returning the condensation by gravity directly to the liquid bath in the container, a relief valve in communication with the vapor space of the container and set to bleed vapor from the container when the vapor pressure in the container rises above the pressure which corresponds with the temperature at which the refrigerating apparatus is intended to maintain the stored carbon dioxide but before the vapor pressure reaches the working pressure of the container, and means for conducting the liquid carbon dioxide at substantially its stored subatmospheric temperature to a point of discharge.

9. A fire extinguishing system comprising a

storage container having a working pressure substantially below the vapor pressure of carbon dioxide at atmospheric temperature and adapted to be filled substantially to its volumetric capacity with liquid carbon dioxide at a subatmospheric temperature, the corresponding vapor pressure of which will not exceed the working pressure of the container, a mechanical refrigerating apparatus including an evaporator coil arranged in heat exchange relation with the vapor of the storage container to prevent a rise in vapor pressure above the working pressure of the container by condensing the vapors and returning the condensation to the liquid bath, and means for conducting the liquid carbon dioxide at a subatmospheric temperature to a point of discharge.

10. A fire extinguishing system comprising a storage container including a vapor receiving space in communication with the container and having a working pressure substantially below the vapor pressure of carbon dioxide at atmospheric temperature adapted to be filled substantially to its volumetric capacity with liquid carbon dioxide at a subatmospheric temperature, the corresponding vapor pressure of which will not exceed the working pressure of the container, a mechanical refrigerating apparatus including a cooling coil arranged in the said vapor receiving space of the container to prevent a rise in vapor pressure above the working pressure of the container by condensing vapors coming in contact with said coil and returning the condensation by gravity directly to the liquid bath in the container, and means for conducting the liquid carbon dioxide 35 at a subatmospheric temperature to a point of discharge.

11. A fire extinguishing system comprising an insulated storage container adapted to be filled substantially to its volumetric capacity with liquid carbon dioxide at a subatmospheric temperature, a mechanical refrigerating apparatus including a cooling coil arranged in the vapor space of the insulated storage container to prevent a rise in vapor pressure above that which corresponds with the subatmospheric temperature of the charged carbon dioxide by condensing vapors coming in contact with said coil and returning the condensation by gravity directly to the liquid bath in the container, and means for conducting the liquid carbon dioxide substantially its stored subatmospheric temperature to a point of discharge.

12. A fire extinguishing system comprising an

insulated storage container adapted to be filled substantially to its volumetric capacity with liquid carbon dioxide at a subatmospheric temperature not to exceed 32° F., said container including a dome arranged to receive vapor rising from the liquid bath in the container, a mechanical refrigerating apparatus including a cooling coil arranged in the vapor receiving dome of the container and operating to prevent a rise in vapor pressure above that which corresponds with the subatmospheric temperature of the charged liquid carbon dioxide by condensing vapors coming in contact with said coil and returning the condensation by gravity directly to the liquid bath in the container, and means for conducting the liquid carbon dioxide at substantially its stored subatmospheric temperature to a point of discharge.

13. A fire extinguishing system comprising an insulated storage container having a capacity of several hundred pounds of liquid carbon dioxide and a working pressure substantially below the vapor pressure of carbon dioxide at atmospheric temperature and adapted to be filled substantially to its volumetric capacity with liquid carbon dioxide at a subatmospheric temperature, the corresponding vapor pressure of which will not exceed the working pressure of the container, a mechanical refrigerating apparatus including an evaporator coil located within the interior of the storage container in heat exchange relation to the carbon dioxide stored therein and connected by piping to the remainder of the apparatus which is located outside of said container, a piping system including a single pipe line leading from the container through which all of the discharged carbon dioxide liquid must pass and a plurality of branch lines connected with said single pipe line and leading to a plurality of points of discharge, said piping system being adapted for conducting the liquid carbon dioxide at substantially its stored subatmospheric temperature to all of said points of discharge, a valve device located in the single pipe line adjacent the storage container and operable to normally exclude the liquid carbon dioxide from the remainder of the system, and a valve device for each branch line operable to select the point or points of discharge after the liquid carbon dioxide has been turned into the piping system by the first mentioned valve device.

ERIC GEERTZ.
